UNITED STATES PATENT OFFICE

CLYDE ALLEN, OF DES MOINES, IOWA, ASSIGNOR TO C. E. ERICKSON COMPANY, INC.,
OF DES MOINES, IOWA

MULTICOLOR-PRINTING PRESS

Application filed January 25, 1928. Serial No. 249,334.

The object of my invention is to provide a multi-color printing press of simple, durable, and comparatively inexpensive construction.

More particularly it is my object to provide a printing press in which a process is utilized which consists of inking a plurality of cuts or the like with different colors of ink and the successive transfer from the cuts (type faces) to a transfer roll of the rubber blanket type, these impressions being then simultaneously transferred to the work which is fed to the press.

Another object is to provide a printing press in which standard type and cuts are used and by an offset process, offset work is produced without the expense of having the cuts reversed or having a stock of reverse type which is necessary in ordinary offset work.

Still another object is to provide an apparatus and a process whereby a printing roll is adapted to receive the impressions from the transfer roll and to then print them simultaneously upon the work.

Still a further object is to provide a printing press which produces multi-color printing with one impression on the work and thereby eliminates the necessity of drying one color before the next one is applied.

It is a common practice among printers to print in colors by providing a series of cuts. Each of the series is used for making an impression in one color. Thus in printing a complete picture, one color, for instance, red, is deposited from one cut for forming part of a completed picture, another color, for instance blue, is printed from another cut for making another part of the completed picture and so on.

In ordinary pictures, the depositing of the impressions from the different cuts is done at successive operations. Usually the ink is allowed to dry after one impression is taken and before the next impression is taken. However, whether the successive impressions are separated by short or longer intervals of time, it is extremely difficult to secure accurate registration of colors, because the

paper stock contracts, expands and stretches depending upon its nature, variations in humidity and variations in temperature.

A further object of my present invention therefore is to provide a machine and process, whereby the aforementioned difficulties in securing registration are eliminated by depositing impressions from the various cuts or type faces upon a single transfer element or upon a single printing roller, so that when the printing impression is made all of the different colors are transferred to the printing stock at one operation. I thus eliminate the problem of securing proper registration arising from variations in the condition of the stock.

Where one color is deposited on stock at one impression and another color at another impression, it becomes of great importance to register the stock on the press with extreme accuracy for the successive operations. By the use of my process and apparatus, this problem is entirely eliminated because of the fact that all of the colors are deposited on the stock at one impression.

However, with my process and apparatus, it is necessary to secure accurate registration of colors on the printing element, when these colors are taken from a plurality of cuts, and this registration I secure by certain novel features of construction and combinations hereinafter more fully set forth.

Still a further object is to design my press so that flat cuts can be used in it even though it is of the rotating type whereby ordinary stock cuts which are in considerable circulation in the present day can be readily used in my machine and new cuts of special design will not have to be made for the customers.

Still a further object is to provide in a press of this kind a work supporting carriage which oscillates through a predetermined path so that work may be placed thereon and carried thereby while it is being printed.

Still a further object is to provide mechanism for rotating the transfer roll and printing roll so that they at all times synchronize during the rotation of the press and

to further provide in connection with this mechanism, means for positively insuring that no slippage of the transfer roll surface relative to the cut surfaces or the printing roll surface will occur.

Still a further object is to provide a stationary platen to support the cuts or the like so that they can be inked with different colors of inks, the transfer roll may receive impressions from them (whereby the several impressions are all assembled in one group, parts of one impression overlapping the other if necessary) and the printing roll may receive the impressions from the transfer roll for depositing them simultaneously upon the work in the press, all of these rolls being rotatably mounted.

Still a further object is to provide a modified form in which the platen itself is rotatable and the inking and transfer rolls are stationary relative to the platen although they are pivotally mounted for contacting with only certain of the cuts, and to provide in connection with a press of this type a printing blanket affixed to the rotating platen itself.

With these and other objects in view my invention consists in the construction, arrangement and combination of the various parts of my device, whereby the objects contemplated are attained, as hereinafter more fully set forth, pointed out in my claims, and illustrated in the accompanying drawings in which:

Figure 1 is a side elevation of my multi-color printing press.

Figure 2 is a vertical sectional view thereof taken on the line 2—2 of Figure 1.

Figure 3 is a horizontal sectional view taken on the line 3—3 of Figure 2.

Figure 4 is a vertical sectional view taken on the line 4—4 of Figure 1 and illustrates the mechanism for oscillating the work supporting carriage.

Figure 5 is a detail sectional view on the line 5—5 of Figure 2 showing the construction of the work supporting carriage.

Figure 6 is a sectional view similar to a portion of Figure 2 illustrating the work supporting carriage and the printing roll in two different positions other than Figure 2, one of these positions being in solid lines and the other being in dotted lines.

Figure 7 is a vertical sectional view on the line 7—7 of Figure 1 showing the limit cam used in my press and omitting a roll drive gear which would actually appear in front of the limit cam.

Figure 8 is a vertical sectional view on the line 8—8 of Figure 1 illustrating a transfer roll cam.

Figure 9 is a vertical sectional view on the line 9—9 of Figure 1 illustrating the ink roll cams and their relation to the ink roll cradles.

Figure 10 is an enlarged sectional view on

the line 10—10 of Figure 1 illustrating a gear train between an anti-lash pinion on the transfer roll and a pinion on the printing roll.

Figure 11 is a sectional view on the line 11—11 of Figure 10.

Figure 12 is a sectional view on the line 12—12 of Figure 2 and illustrates one of the ink roll cradles and the parts supported thereby.

Figure 13 is an enlarged sectional view on the line 13—13 of Figure 12.

Figures 14 and 15 are views similar to the left hand end of Figure 12 illustrating portions of the other two ink roll cradles showing the relation of certain parts thereon to the first ink roll cradle and to the various ink roll cams of the printing press.

Figure 16 is an enlarged sectional view through either the transfer roll or the printing roll illustrating its construction.

Figure 17 is a sectional view on the line 17—17 of Figure 2 illustrating the manner of securing a chase to one of the platen surfaces of the platen.

Figure 18 illustrates a sectional view through a printing press of modified construction in which the platen rotates instead of remaining stationary and a portion of the rotating member is provided with a rubber blanket to serve in place of the printing roll; and

Figure 19 illustrates the same idea as designed for the use of arc-shaped cuts which are usually cast in lead and are used extensively by newspapers.

On the accompanying drawings I have used the reference numeral 10 to indicate a supporting base on which the various parts of my multi-color printing press are mounted.

The base 10 may either rest on a table or other support or may be provided with supporting legs if so desired.

Extending upwardly at the forward end of the base 10 is a frame member 12. A similar frame member 14 with the exception of being of a different shape extends up from the rear end of the base. The frame members 12 and 14 are provided for supporting a stationary shaft 16. In order to support the shaft 16 and securely clamp it to the members 12 and 14 I provide these members with one side slit as indicated at 18 and I use a cap screw 20 in each of the members for securely clamping the shaft 16 relative to the hubs formed on the upper center portions of the members 12 and 14.

Keyed and clamped to the shaft 16 is a platen 22 having a plurality of platen surfaces 24, 26, and 28. A bushing 30 (best illustrated in Figure 3 of the drawings) is secured to the platen 22 and keyed to the shaft 16. Keyed to the bushing 30 is a roll drive gear 158, a limit cam 34, a transfer roll cam 36 and three ink roll cams 38, 40, and 42. From the forego-

ing description it will be obvious that the gear 158 and the cams 34, 36, 38, 40, and 42 as well as the platen 22 are mounted stationary relative to the base of the printing press. Rotatably mounted on the shaft 16 and surrounding the platen, the roll drive gear and the various cams, is a cage like rotor consisting of a front rotor head 44, a rear rotor head 46 and tie members 48. The rotor heads 44 and 46 are provided with ball bearings 50 so that proper alignment and free running of the parts are always insured.

The rotor head 46 is provided with a sleeve like extension 52 extending toward the rear of the press and attached to a rotor gear 54. The gear 54 is provided with a ball bearing 55. A pair of work carriage actuating cams 56 and 58 is keyed to the sleeve 52. From the construction of the parts just described it will be obvious that whenever the gear 54 is rotated the cams 56 and 58 and the rotor heads 44 and 46 together with the tie members 48 will rotate. For rotating the rotor gear 54 I provide a pinion 60 best shown in Figure 4 which is mounted on a shaft 62. The shaft 62 is rotatably mounted in ball bearings in a bracket 64 and in the frame member 14. A pulley 66 is secured to the shaft 62 and may be belted to an electric motor for the purpose of driving the press. Any type of starting and stopping mechanism such as a clutch and brake may be employed for operatively connecting the electric motor to the pulley 66 or disconnecting it therefrom.

To each of the platen surfaces 24, 26, and 28, I secure chases 68, 70, and 72. (See Figs. 2 and 17.) Each chase is of the ordinary construction comprising a frame into which a wooden block 74 may be locked by the insertion of blocking 76, (commonly called furniture) and set screw means for clamping the furniture against the block. The block 74 has on its surface ordinary printers' type 78 which is standard. Instead of the type, a half tone photograph or line cut, cast in a lead composition may be secured to the block 74. The combination of the block 74 and the type 78 is commonly known as a cut and will hereinafter be referred to as cuts A, B, and C.

The chases themselves are clamped to the platen surfaces in the following described manner. (See Figure 17.) Extending from the drive gear 158 is a pin 33 adjacent the center of each platen surface. The chases 68, 70, and 72 are each provided with an opening 73 adapted to receive either of the pins 33. Thus the surface of the drive gear 158 serves to align the chase when the chase is forced thereagainst and the pin 33 centers the chase so that the cuts A, B, and C will be precisely positioned on the platen surfaces.

For forcing the chase against the gear I provide a clamp bar 23 secured to a lug

22^a extending inwardly from the platen frame by means of a cap screw 23^a. The inner end of the bar 23 engages a flange 69 on the hub of the platen and the outer end of the bar engages in a groove 71 of the chase. The chase is forced to contact with the gear 158 by tightening the screw 23^a. Thus the chases are readily removable and can be interchanged when it is desired to exchange the colors on the finished work.

75

Inking mechanism

It is desirable to ink each of the cuts A, B, and C with a different color of ink and in order to do this, I provide ink rolls 80, 82, and 84 (Figure 2). Each ink roll is made of composition or rubber and is mounted on a shaft 86. A cradle 88 is provided for supporting each of the ink rolls 80, 82, and 84 and since these cradles are similar I will describe but one of them giving the parts of the others the same reference numerals with the addition of the characters "a" and "b". In the embodiment of my press as here illustrated I have shown three cuts and three ink rolls. However it is obvious that any number of cuts and ink rolls may be used by designing the press larger. In this manner any desired number of colors can be printed.

Figure 12 illustrates the cradle 88 which comprises a U-shaped portion 90 having bosses 92 and 94 formed on its ends. Extending from the bosses 92 and 94 are trunnions 96 which are mounted in ball bearings 98. The ball bearings 98 are supported by brackets 100 extending from the rotor heads 44 and 46. Thus it will be seen that the cradle 88 is pivotally mounted so that it can be rocked as the printing press rotates.

Mounted in the ends of the U-shaped portion 90 are ball bearings 102 which receive trunnions 104 formed on the shaft 86 of the ink roll. A pinion 108 is also mounted on the shaft 86. The ink roll and the pinion 108 all rotate with the shaft 86 and the mechanism to cause such rotation I will hereinafter describe.

An ink fountain and necessary distributor may be provided for the ink roll. In order to evenly distribute the ink on each ink roll I may provide a distributor roll 110. The distributor roll 110 is rotatably mounted on a shaft 112. Secured to the shaft 112 inside the roll 110, which is of hollow construction, is a bevel pinion 114. Mounted on the shaft 112 for rotation with the roll 110 is a supporting member 116 for rotatably supporting a bevel gear 118. The gear 118 meshes with the pinion 114 and is connected by a link 120 to a pin 122 mounted in one end of the roll 110. A collar 124 is pinned to the shaft 112 and the member 116 rotates between this collar and the bevel pinion 114.

The shaft 112 is held against rotation and is constrained to move toward the ink roll

130

80 by the following described mechanism. Slidably and rotatably mounted in openings 126 formed in the U-shaped portion 90 is a pair of pins 128 (Figs. 12 and 13). One end of each pin 128 terminates in a stem 130 which extends through a flange 132 and an enlarged opening 134. Lock nuts 136 are mounted on the free ends of the stem 130 and a spring 138 is interposed between the lock nuts 136 and the flange 132.

Formed in one of the pins 128 is a slot opening 140 and formed in the other pin 128 is an L-shaped notch 142. The ends of the shaft 112 are flattened as at 144 so that they can engage in the slot 140 and the notch 142. To assemble the distributor roll 110 in the cradle 88 first one end of the shaft 112 is inserted in the slot 140 and the other end thereof is then inserted in the notch 142. The springs 138 will thereafter serve to keep the distributor roll 110 in close contact with the ink roll so that the ink roll will, upon rotation impart rotation to the distributor roll 110.

As the distributor roll 110 is rotated, the bevel gear 118 will also rotate and due to its link connection 120 with the distributor roll head, the distributor roll will move back and forth longitudinally on the shaft 112 as it rotates. This evenly distributes the ink on the ink roll. It is obvious that any other practical type of distributing mechanism might be used in place of the one I have shown, for the purpose of insuring that the ink will evenly coat the ink roll 80 so that a good job of printing results when the press is operated.

Pivotedly mounted on a lug 146 extending from the boss 92 is an arm 148 (Fig. 12). A cam roller 150 is rotatably mounted on the end of the arm 148 and is designed to coact with the ink roll cam 42. For maintaining the arm 148 rigid relative to the boss 92 I provide a set screw 152 threaded in one end of the arm 148 for bearing against the boss 92. The set screw 152 also serves as a means of adjustment whereby the path of the ink roll may be varied relative to the cam surface of the cam 42. For keeping the roller 150 tight against the cam 42 I provide an arm 154 formed on the boss 92 and a spring 156 connecting this arm to one of the tie members 48 of the rotor serves to hold the roller 150 against the cam 42.

The cradles 88 for the ink rolls 82 and 84 have similar arms 148^a and 148^b with rollers 150^a and 150^b adapted to engage the ink roll cams 40 and 38 respectively. Arms 154^a and 154^b and springs 156^a and 156^b serve to hold the rollers 150^a and 150^b against the cams 40 and 38.

For rotating the pinion 108 and consequently the ink roll 80 and distributor roll 110 I provide a gear 158 of special design. The gear 158 has a circumferential portion 160 and rack portions 162 whereby half of it is of substantially hexagon shape and the other

half is semicircular. This is clearly illustrated in Figure 2 of the drawings. The pinion 108 during the travel of the cradle 88 as the printing press rotates, meshes with the gear portion 160 and the rack portions 162 of the gear 158. In this manner the ink rolls 80, 82, and 84 rotate at all positions during their travel as the printing press rotates.

It is desirable in multi-color work that each of the ink rolls be supplied with a different color of ink and that each ink roll ink only one of the cuts A, B, and C and none of the others. In order to accomplish this, the cam 38 is provided with a high portion 38^a which causes the roller 80 to contact with the cut A (Figs. 2 and 9). The high portions 38^b and 38^c of the cam 38 are lower than the portion 38^a so that as the ink roll 80 travels past the cuts B and C it will not contact with them but yet the pinion 108 will remain in mesh with the rack portions 162 of the gear 158. In this manner only the cut A is inked by the ink roll 80 and yet the ink roll rotates throughout its entire travel until it is again in position to ink the cut A.

In a similar manner the cams 40 and 42 are provided with corner portions 40^a and 42^a which are higher than the other two corner portions of these cams so that the ink roll 82 will ink only the cut B and the ink roll 84 will ink only the cut C.

In Figure 7 I have illustrated the roll 80 as contacting with the cut A and as it continues in its travel, it will be raised by the spring 156 from the cut B and also from the cut C as illustrated by the dotted line 164.

The printing roll

Extending from one of the tie members 48 is a pair of brackets 170 and 172 (Fig. 1). The bracket 170 is provided with a ball bearing adapted to receive one end of a shaft 176. The other end of the shaft 176 is enlarged as indicated at 178 (Figures 11 and 16) and is covered with a rubber blanket 180. A socket is formed in the portion 178 of the shaft to receive a ball bearing 182 which is mounted on a trunnion 184 extending from the bracket 172. A roller 186 and a pinion 188 are mounted on the shaft 176. The rubber blanket 180 is held on the portion 178 by a lock bar 190 having pins 192 extending through openings formed in the edges of the blanket. The edges of the blanket and the bar 190 are mounted in a longitudinal depression 194 formed in the portion 178 of the shaft 176. Screw means 196 are provided for holding the bar 190 in position in the depression 194. The shaft 176 and the blanket 180 mounted thereon form a rotatable printing roll which I will designate generally by the reference character D.

From the foregoing description, it will be obvious that rotation of the rotor will carry with it the printing roll D in a circular

path. Means for rotating the printing roll D will hereinafter be described.

Transfer roll mechanism

In the construction of my press I provide a transfer roll E, comprising an enlarged shaft 198 covered with a rubber blanket 200 which is held to the shaft 198 in a manner similar to that for holding the blanket 180 to the shaft 176. The ends of the shaft 198 are journaled in ball bearings mounted in arms 202 extending from a rock shaft 204. The ends of the rock shaft 204 are mounted in ball bearings 206 which are supported by brackets 208 extending from the rotor heads 44 and 46.

An arm 210 extends from the rock shaft 204 and has rotatably mounted on its free end, a roller 212 adapted to coat with the transfer roll cam 36. The transfer roll cam 36 is best illustrated in Figure 8 of the drawings and comprises a circumferential portion 214 and raised portions 216. The raised portions 216 contacting with the roller 212 as the printing press rotates causes the transfer roll E to contact with each of the cuts A, B, and C so as to receive the impression from each so that after having passed all three of them, the impression on the transfer roll consists of three separate impressions of three distinct colors, assembled to produce a composite three-color reproduction. During the travel of the transfer roll E as the press rotates it will be rotated in its bearings by a pinion 218 (Fig. 11). The pinion 218 meshes with the teeth of the gear 158 in a manner similar to the pinions 108 of the ink rolls. After the transfer roll E has received a completed impression, the roller 198^b contacts with the raised portion 166 of the cam 34 which moves the transfer roll away from the center of the press and causes its contact with the printing roll D. In Figure 8 the path of the surface of the transfer roll is indicated by the dot and dash line 222. When the transfer roll E is moved away from the center of the press and contacts with the printing roll D (which is rotated by a gear train hereinafter to be described) the impression thereon is transferred to the printing roll so that it can be deposited from the printing roll onto the work placed in the press. The rolls D and E remain in contact with each other during just one revolution of them so that the complete impression is transferred from the transfer roll to the printing roll.

For rotating the printing roll D I provide a gear train comprising a pinion 224 journaled between one of the arms 202 of the rock shaft 204 and another arm 226 extending therefrom. Another pinion 228 meshes with the pinion 224 and also with the pinion 188 on the printing roll shaft. The shaft 230 on which the pinion 228 is journaled is supported by a link 232. The link 232 comprises a pair

of sides 232^a and a cross member 232^b. The pinions 224 and 228 are mounted between the sides 232^a. A link 234 connects the shaft 230 and the shaft 176 of the printing roll D. From the construction of the parts just described it will be obvious that rotation is imparted from the pinion 218 through the pinions 224, 228, and 188 to the printing roll D and that the transfer roll E may be moved toward or away from the printing roll D due to the pivotal connections between the links 232 and 234.

While the transfer roll E is in contact with the cuts A, B, and C for the purpose of receiving the impressions therefrom, it is necessary that no slippage occur between the transfer roll surface and the cuts. I have therefore designed the pinion 218 of the anti-lash variety which is best illustrated in Figures 10 and 11 of the drawings. The pinion 218 consists of two separate pinions 218^a and 218^b positioned face to face. The pinion 218^a is keyed to the transfer roll shaft 198 by a key 218^c and the pinion 218^b is free to rotate thereon. Pins 236 are attached to the pinion 218 and extend into slots 238 formed in the pinion 218^b. A spring 240 is interposed between one end of each slot 238 and the pin 236 extending therein. This construction causes the pinions 218^a and 218^b to rotate slightly relative to each other so as to (in effect) enlarge the teeth of the pinion 218. This is clearly illustrated in Figure 10 of the drawings showing the teeth enlarged to fill the teeth of the gear 158. The width of the pinion 224 is such that it meshes only with the pinion 218^b so that the teeth of the pinion 224 will not restrict the enlarging movement of the teeth of the pinion 218. When the transfer roll E is moved to contact with the printing roll D, the pinions 218^a and 218^b enlarge in the teeth of the pinion 188 so that no slippage occurs of the printing roll relative to the transfer roll. The pinion 218 of the transfer roll is moved only far enough away from the gear 158 to mesh with the pinion 188 and yet still mesh, even though loosely, with the gear 158.

Work supporting carriage

Due to the rotation of the printing roll D around the shaft 16 and due to its rotation independent of the shaft, it is necessary to provide a special type of work supporting carriage so that work can be printed on from the printing roll D. The work supporting carriage is best illustrated in Figures 2, 5, and 6 of the drawings and comprises a carriage table 242 having downwardly extending ears 244. Shafts 246 are mounted in the ears 244 and rollers 248 are rotatably mounted on the outer ends of the shafts 246. The rollers 248 are designed to travel in semi-circular tracks 250 formed in carriage track members 252 spaced from each other and extending up from the supporting base 10. The carriage 242 is

normally in the position illustrated in Figure 2 but is designed to move in the direction of the arrow 254 to the other ends of the tracks 250 as shown in Figure 6.

5 A block 256 is designed to fit and support the work 258. I have illustrated a sheet metal plate to be printed on but any other type of device such as match boxes and other advertising novelties may be printed on in a press of this character by designing the block 256 to 10 suit the article. As the printing press rotates, the printing roller D swings through an arc and the work 258 will likewise swing through an arc due to certain carriage actuating mechanism timed to operate according to the operation of the press whereby the printing roll D will roll across the surface of the work as 15 illustrated in Figure 6. To cause rolling of the printing roll D relative to the work 258, the carriage 242 is moved in the direction of the arrow 254 at a slower rate of speed than the printing roll D which moves in the same direction however.

Work carriage actuating mechanism

25 For the purpose of actuating the work carriage 242 and causing its movement in one direction while the work thereon is being printed, and its movement in an opposite direction, 30 while the printing roll is continuing its travel with the rotation of the press, I provide the following described mechanism. Bearings 260 extend from the base 10. A rock shaft 262 is journaled in the bearings 260 and is provided with a pair of upstanding arms 264 connected by links 266 with one of the shafts 246 of the work carriage. A third arm 266^a is formed on the rock shaft 262.

35 Oscillatably mounted in bearings 268 extending upwardly from the bracket 64 and a similar bracket 270 is a carriage actuating lever 272. The lever 272 has pintles extending from opposite sides thereof and into the bearings 268. The lower end of the lever 272 is operatively connected by a link 274 to the 40 arm 266^a. From the foregoing construction it will be obvious that swinging motion of the lever 272 will impart the desired movement to the work carriage 242.

45 Rotatably mounted on the lever 272 is a pair of cam rollers 276 and 278. The roller 276 coacts with the cam 56 and the roller 278 coacts with the cam 58. The cam 58 serves to move the carriage 242 in the direction of the arrow 254 and the cam 56 serves to return it to the original position illustrated in Figure 2. When the carriage is in the dotted line position illustrated in Figure 6, the carriage actuating arm 272 is in the dotted line position 50 illustrated in Figure 4.

55 The cam 58 is provided with an abrupt rising portion 58^a and a gradual retiring portion 58^b so that the work 258 is moved quickly in the direction of the arrow 254 in accordance with the rotation of the printing roll D

60 past the work and thereafter the carriage 242 is slowly returned so that the operator can remove the printed work therefrom and insert in place another piece to be printed. The cam 56 is provided with an abrupt rising portion 56^a and a gradual retreating portion 56^b oppositely arranged relative to these portions of the cam 58 so that the two cams at all times move the actuating lever 272 positively in both directions. The journal pins 280 on 65 which the rollers 276 and 278 are mounted may be eccentrically mounted in the actuating lever 272 so that slight adjustment can be had. For the same reason the pin 282 on which the transfer roller 212 is mounted may 70 be journaled eccentrically in the arm 210.

75 On the transfer roll shaft E a bushing 198^a is interposed between the bearing 202 and the gear 218. Rotatably mounted on this bushing is a cam roller 198^b adapted to coact with the limit cam 34 so that as the transfer roll E is receiving impressions from the cuts A, B, and C, it will contact with these cuts just 80 sufficiently to properly receive the impressions.

85 Since the transfer roll cam 36 is provided with a depression 220 for allowing the transfer roll E to contact with the printing roll D as shown in Figure 8 it is necessary to provide the limit cam 34 with a raised portion 166 so that the cam 34 will be in contact with the roller 198^b during the transfer operation (Figs. 7 and 8).

90 Due to any lost motion of the pinions 218, 224, 228, and 188, it is necessary to provide for a positive rotation of the printing roll D as the work 258 is being printed. This is accomplished by mounting a rack 243 on the table 242 in position to mesh with the pinion 188 of the printing roll D as this roll 95 is traveling from end to end of the work 258. This insures that the chance for slippage between printing roll and work will be minimized. To prevent the printing roll D from pressing too tightly against the work and thereby making a smeared impression thereon due to squeezing of the rubber blanket, I provide a cam bar 245. The cam bar is mounted on the table 242 in position to be 100 engaged by the roller 186 on the printing roll shaft as the printing roll rolls across the surface of the work 258.

105 In Figure 18 I have illustrated a modified form of my invention in which the platen 284 rotates and the ink rolls 286 do not rotate. This is the same idea carried out in Figures 1 to 17 of my drawings with the exception of rotating one part instead of another. In the modification illustrated in Figure 18, the ink rolls 286 are tied by rock 110 shafts 288 so that they can either contact with the cuts 290 or not as necessary. I have illustrated three of the ink rolls 286 as contacting with three of the cuts and the other two ink rolls are arranged to contact with the remain- 115 120 125 130 135 140 145 150 155 160 165 170 175 180

ing two cuts so that there is an inking roll for each cut and five different colors may be impressed on the transfer roll 292. When the machine is designed as illustrated in Figure 18, it is not necessary to have an additional printing roll but a printing blanket 294 may be secured to a portion of the rotating platen 284 and receive the impression from the transfer roll 292. The impression on the blanket 294 may be then transferred to sheets of paper or the like 296 which are fed between the blanket and a supporting roll 298. A cam 300 is provided for each ink roll 286 and for the transfer roll 292 which serves to move them into and out of contact with the cuts and also to move the transfer roll 292 in contact with the blanket 294 and the ink rolls 286 to position where they do not contact with this blanket.

I have shown one cam 300 for the ink roll 286 and have illustrated a roller 302 mounted on an arm 304 and adapted to coat with the periphery of the cam. The cam 300 is provided with a portion 306 formed on a radius from the center of the press so as to keep the ink roll 286 from contacting with the blanket 294. In Figure 19 I have illustrated a modified form of construction in which the platen 308 is circular for receiving cuts 310 which are usually cast in lead and used extensively for the printing of newspapers. In this construction no provision is necessary for moving the transfer roll 312 toward or away from the center of the machine as the transfer roll must contact with each cut 310 and then with the printing blanket 314. The cam 316 used for the lowermost ink roll 318 is in the form of a circle with a raised portion 320 adapted to cause the ink roller to contact with its respective cut 310. After the raised portion 320 has passed the roller 322, the ink roll 318 will drop to position where it does not contact with any of the other cuts.

From the foregoing description it will be seen that I have provided a process by which a plurality of colors may be first impressed on one transfer roll and thereafter deposited all at one time on the work so that it is necessary to provide only for proper register of the transfer roll with the various cuts instead of making several impressions on the work in which case the work would have to be delicately positioned so that these several impressions would register perfectly. The advantage of such a construction is very obvious as one printing operation on the work is all that is necessary even though a great number of colors are used. Furthermore, I have provided for the adaptation of my press for the general type of cuts used by manufacturers and the like so that their cuts can be used in my machine and new cuts will not have to be made. By the provision of a transfer roll and a printing roll ordinary printers' type can be set up in my machine

and by the double offset process I have outlined in my description, the printing on the work will be in proper position for reading.

My printing process and press make it possible to print several different colors within the same outline, or with parts of one color overlapping the other, all at one application of the impression upon the work. The difficulties experienced in printing presses where first one color is impressed on the paper and then another color is impressed and so on, are that the paper stretches or shrinks between impressions unless the humidity and temperature of the room remains constant and even then the roll of paper must be thoroughly tempered throughout to the humidity and temperature of the press room before printing is started. The difficulty is greatly increased where it is necessary to dry the ink between operations and before the next impression is applied. Where sheet metal stampings are printed as illustrated in my drawings, slight variations in the dimensions will often cause non-registry of the impressions when the work is put on the block 256 for each impression of separate color.

In my process these difficulties are entirely overcome because of having the registry occur on elements of the press instead of on the work. Since these elements are all parts of a machine operating in the same room they will therefore at all times respond exactly alike to the factors of humidity and temperature. By the provision of ball bearings throughout the press, the misalignment experienced with contraction and expansion of bronze bushings and other types of bearings is overcome. The anti-lash gear takes care of all looseness occurring between the drive gear and pinions on the transfer and printing rolls due to wear so that proper registry is insured at all times.

There are many other advantages inherent in a structure of this kind. For example, it is possible to use three chases. In two of the chases, I may place cuts for printing parts of a reproduction in two colors. In a third chase, I may place type for printing either in a different color or in one of the colors used for the cuts.

The cuts may be used for several jobs while the type is used for only one job. The chases containing the cuts may be left in the machine, and the chase containing the type may be taken out and a form containing other type inserted in the chase, and the chase replaced, and a new reproduction made employing the same cuts and different ink, the change requiring only the replacing of one chase.

Various changes such as modifications as I have shown in Figures 18 and 19, may be made in the construction and arrangement of the parts of my device without departing from the real spirit and purpose of my in-

vention, and it is my intention to cover by my claims, any modified forms of structure or use of mechanical equivalents, which may be reasonably included within their scope.

I claim as my invention:

5. 1. A multi-color printing press comprising a printing blanket adapted to travel in a circular path and to print an impression on a piece of work fed to the press at each revolution thereof, a plurality of cuts or the like supported in said press, an ink roll for each cut or form whereby each cut or form may be inked with a different color of ink, a transfer roll adapted to contact with each of said cuts or forms after they are inked and to thereafter contact with the printing blanket whereby all impressions received by the transfer roll are simultaneously deposited on said blanket, and means for rotating said transfer roll to synchronize with the rotation 10 of the press whereby perfect register of the impressions received from the several cuts or forms results, said means comprising a series of teeth adjacent each cut and an anti-lash pinion on said transfer roll adapted to coact with said teeth.

2. A printing press comprising a platen having a plurality of platen surfaces, a cut or the like secured to each of said surfaces, a plurality of ink rollers adapted to each ink a cut or form of said plurality of cuts or forms with a different color of ink, a transfer roll adapted to contact with each of said cuts or forms to receive impressions from them, means for rotating said ink rolls and said transfer roll comprising pinions on said rolls and teeth adjacent the platen surfaces for meshing with said pinions and a printing roll for first receiving the impressions from the transfer roll and then depositing said impressions onto work fed to the press, said transfer roll being provided with an anti-lash pinion to insure perfect register of the impressions received from the several cuts or forms and deposited on the transfer roll.

40. 3. A printing press comprising a platen having a plurality of platen surfaces, a cut or the like secured to each of said surfaces, a plurality of ink rolls adapted to each ink a cut or form of said plurality of cuts or forms with a different color of ink, a transfer roll adapted to contact with each of said cuts or forms to receive impressions from them, means for rotating said ink rolls and said transfer roll comprising pinions on said rolls and teeth adjacent the platen surfaces for meshing with said pinions, said transfer roll being provided with an anti-lash pinion to insure perfect register of the impressions received from the several cuts or forms and on the transfer roll, a printing roll adjacent said transfer roll, a pinion thereon, means for engaging said anti-lash pinion and said printing roll pinion together after the transfer roll 45 has received the impressions from the cuts

or forms whereby the transfer roll and the printing roll contact with each other, the printing roll receiving all said impressions simultaneously and the anti-lash pinion insuring against slippage of the transfer roll surface relative to the printing roll surface.

4. In a printing press for printing different colors simultaneously on a piece of work, a base, a stationary shaft supported thereabove, a polygonal shaped platen supported on said shaft, a cut or the like secured to each of the platen surfaces of said platen, a cage like rotor surrounding said platen and rotatably supported on said shaft, a series of ink roll cradles pivoted on said rotor, an ink roll carried by each cradle and adapted to ink a certain one of said cuts or forms, a transfer roll cradle pivoted on said rotor, a transfer roll carried thereby and adapted to receive an impression from each of said cuts or forms and means for simultaneously depositing the impressions thus received onto work placed in the press, said last means comprising a printing roll to receive the impressions from the transfer roll and thereafter contact with such work.

5. In a multi-color printing press, a printing roll adapted to travel in a circular path, means for depositing a plurality of different colored impressions thereon and thereafter depositing all of said impressions at one time onto work placed in the press and a work carriage adapted to receive said work and to travel in a semicircular path as the work is being printed.

6. A multi-color printing press comprising a polygonal shaped platen, a cut or the like secured to each of the platen surfaces thereof, a plurality of ink rolls adapted to travel in a polygonal path and deposit ink of various colors on said cuts, or forms, means for causing each of said rolls to contact with only one of said cuts or forms, a transfer roll adapted to receive an impression from each of said cuts or forms whereby the complete impression thereon comprises all the colors used, a printing blanket for receiving the complete impression from the transfer roll and means for depositing with a rolling line contact the impression thus received onto work placed in the press.

7. A multi-color printing press comprising a polygonal shaped platen, a cut or the like secured to each of the platen surfaces thereof, a plurality of ink rolls adapted to travel in a polygonal path and deposit ink of various colors on said cuts or forms, means for causing each of said rolls to contact with only one of said cuts or forms, a transfer roll adapted to travel in a polygonal path and thereby receive an impression from each of said cuts or forms whereby the complete impression thereon comprises all the colors used, a printing blanket for receiving the complete impression from the transfer roll and means for

depositing the impression thus received onto work placed in the press with a rolling line contact.

8. In a printing press of the character described, a series of chases containing cuts or the like, means for inking the cut or form in each chase with a different color of ink, a transfer roll for receiving the impression from each of said cuts or forms whereby the completed impression on said transfer roll includes all the colors used, a printing roll adjacent said transfer roll, means for moving the transfer roll to contact with the printing roll whereby said printing roll receives the completed impression and means for thereafter depositing the completed impression on work fed to the press.

9. A multi-color printing press comprising a polygonal shaped platen, a cut or the like secured to each of the platen surfaces thereof, a plurality of ink rolls adapted to travel in a polygonal path and deposit ink of various colors on said cuts or forms, means for causing each of said rolls to contact with only one of said cuts or forms, a transfer roll adapted to receive an impression from each of said cuts or forms whereby the complete impression thereon comprises all the colors used, a work carriage for receiving work to be printed, means for depositing the impression from the transfer roll onto the work received by the work carriage and means for moving the carriage while the work thereon is being printed.

35 10. In a printing press for printing different colors simultaneously on a piece of work, a base, a stationary shaft supported thereabove, a polygonal shaped platen supported on said shaft, a cut or the like secured to each of the platen surfaces of said platen, a cage like rotor surrounding said platen and rotatably supported on said shaft, a series of ink roll cradles pivoted on said rotor, an ink roll carried by each cradle and adapted to ink a certain one of said cuts or forms, a transfer roll cradle pivoted on said rotor, a transfer roll carried thereby and adapted to receive an impression from each of said cuts or forms, a printing roll carried by said rotor in proximity to said transfer roll, means for rocking the transfer roll for causing its contact with the printing roll and thereby depositing the impressions received thereon onto the printing roll and a work carriage adapted to support work in position to receive the impressions from the printing roll.

11. In a printing press, a printing roll adapted to travel in a circular path and a work carriage adapted to receive work and to travel in a semicircular path as the printing roll contacts with the work on said carriage.

12. In a printing press, a printing roll adapted to travel in a circular path and a work carriage adapted to receive work and to travel in a semicircular path as the printing

roll contacts with the work on said carriage, the radius of the semicircular path being different than the radius of the path of the printing roll whereby the printing roll travels with respect to the surface of the work on which it prints.

13. In a printing press, a plurality of cuts or the like, means for inking each one with a different color of ink, a transfer element adapted to coat with each cut to receive an impression therefrom and means to insure perfect register of such impressions on the transfer element, said means comprising a geared connection between the cuts and the transfer element, such connection including anti-lash gear teeth.

Des Moines, Iowa, December 31, 1927.

CLYDE ALLEN.
